UNITED STATES PATENT OFFICE.

JOZEF SORDYKA, OF GRAND RAPIDS, MICHIGAN.

DESIGN FOR A SWORD-HANDLE.

52,354.

Specification for Design. Patented Aug. 27, 1918.

Application filed December 6, 1917. Serial No. 205,897. Term of patent 7 years.

To all whom it may concern:

Be it known that I, JOZEF SORDYKA, a citizen of the United States of America, residing at Grand Rapids, in the county of Kent and State of Michigan, have invented a new, original, and ornamental Design for a Sword-Handle, of which the following is a specification, reference being had to the accompanying drawing, forming part thereof.

The figure is a side elevation of a sword handle, showing my new design.

I claim:—

The ornamental design for a sword handle, as shown. JOZEF SORDYKA.

Copies of this patent may be obtained for five cents each, by addressing the "Commissioner of Patents, Washington, D. C."
